GAME BOARD

Frank W. Collett, Box 943, Fort Pierce, Fla. 33450

Filed Jan. 16, 1970, Ser. No. 20,959

Term of patent 14 years

Int. Cl. D21—02

U.S. Cl. D34—5

FIG. 1.

FIG. 2.

FIG. 3.

FIG. 1 is a plan view of the game board showing my new design;

FIG. 2 is a side elevation of said game board;

FIG. 3 is a sectional view taken along line 3—3 of FIG. 1 and looking in the direction of the arrows;

FIG. 4 is a fragmentary bottom view of the game board the unshown portions of the bottom of the board being unadorned and plain except for the square, triangular and circular openings arranged as visible in FIG. 1 to receive game pieces.

Portions of the game board are stippled to show contrasting colors.

I claim:

The ornamental design for a game board, as shown and described.
